UNITED STATES PATENT OFFICE.

ELBERT G. CHANDLER, OF PORTLAND, OREGON.

LOGGING-TRUCK.

1,380,315.

Specification of Letters Patent. Patented May 31, 1921.

Application filed November 6, 1919. Serial No. 336,168.

To all whom it may concern:

Be it known that I, ELBERT G. CHANDLER, a citizen of the United States, and a resident of Portland, county of Multnomah, and 5 State of Oregon, have invented a new and useful Improvement in Logging-Trucks, of which the following is a specification.

The object of my invention is to provide a logging truck having a frame and pedestal construction affording great strength, so as to be adapted for withstanding, without undue wear and tear, the abuse to which logging trucks are subjected in logging service. In this respect I have particularly in mind 15 the making of the ends of the truck of such construction as to be adapted to withstand the blows which in service are frequently delivered by logs against the sides of the trucks and by which, in the prior construction, the ends of the trucks were thrown out of alinement, causing the displacement of the transverse end sills carrying the coupling elements, and throwing the latter out of alinement to such extent that the truck 25 was unfit for further service until repaired.

It is further my object to obtain such result by a construction which will not increase the cost of manufacture over the common logging truck, but instead, tend to 30 cheapen the cost.

I attain my object by making my truck frame and the pedestals of a construction substantially solid, embodying the following predominant features:

35 The frame of the truck is made of solid, or one-piece sides, preferably consisting of I-beams, having spaces cut out near the ends for inserting pedestals. The pedestals are castings adapted for being inserted in said 40 spaces, and for being rigidly fastened in place. Furthermore the solid sides are made of such length as to project a substantial distance beyond the pedestals, and thus provide a solid support on which to mount 45 the end frame-members, and coupling elements.

The details of the above described features of my invention and other incidental features are illustrated in the accompanying 50 drawings in which:

Figure 1 is a side elevation of my truck, in the left end of which is shown the pedestals and journal-box, but the near pedestal

of the right end of the truck frame being omitted;

Fig. 2 is an end view of my truck, the right side showing a pedestal and the journal-box carried thereby, but such parts being omitted from the left side;

Fig. 3 is a detail of one of the solid sides 60 of my truck frame, and connecting transverse end frame-member;

Fig. 4 is a detail, in perspective, of one of the pedestal castings;

Fig. 5 is a top view of the pedestal 65 casting;

Fig. 6 is a transverse section through one side of the truck frame with a pedestal secured in place, the section being taken through the rivet holes of the overlying portions of the parts; and

Fig. 7 is a similar sectional detail including a journal-box, and the spring seated on the journal-box for supporting the truck frame, the spring bearing in a housing 75 therefor provided in the upper part of the pedestal.

Fig. 8 is a full perspective of the frame of my truck;

Fig. 9 is a larger scale partial plan of the 80 right hand end of Fig. 8, showing details of those portions of the frame carrying the lower coupling element;

Fig. 10 is a longitudinal section approximately taken through the center of Fig. 9; 85

Fig. 11 is a detail of the upper coupling element;

Fig. 12 is a detail of one of the members included in the coupling elements;

Fig. 13 is a perspective view of the guide 90 for the coupling; and

Fig. 14 is another detail of one of the follower plates.

My truck consists of two solid or one-piece sides *a*, preferably made of I-beams. Adjacent each end of the sides is cut out a rectangular space or recess *b*, for inserting a pedestal-casting *c*; leaving however a vertical portion *i* of the web of the side extending across the top of the space or recess *b*. 100 The pedestals are made with transverse inner webs *d* spaced apart and projecting a substantial distance beyond the side faces of the pedestals so as to provide a journal-box bearing. The pedestals are further made 105 with marginal portions or flanges *e* adapted

for overlying the web-portions *f* encompassing the spaces *b*, of the sides. The pedestal casting is provided at the top with a marginal portion or flange *g*, and a companion flange *h*, spaced from the flange *g* so as to permit the vertical side extending across the space or recess *b* to be seated in the groove so formed, and cause said flanges *g* and *h* to overlie the web-portion *i* of the side, and permit the overlying parts to be firmly fastened together by a rivet *m* or other fastening element. The pedestals are further provided at the top with laterally projecting portions *j*, *j'* constituting a dome-like housing for the upper end of the springs *k* to bear in, the lower ends of said springs being seated on the journal-box *l*, which is of the usual construction.

I prefer to fasten the pedestal casting *c* in place by means of rivets as shown at *m* in Fig. 6 thereby avoiding the undesirable effects of bolts becoming stretched, and the nuts of the bolts working off.

The sides *a* and *a'* of the frame are made of such lengths that their ends *n* and *n'* project a substantial distance beyond the spaces or recesses *b*; and on said projecting ends are mounted the transverse end bars, or sills, *o* and *o'* connecting the sides.

Thus the ends of the solid I-beams projecting beyond the journal boxes provide a solid support for the transverse end-sills capable of resisting the blows which are delivered in service against said projecting ends, and thus preventing the displacement of said end-sills and the throwing out of alinement of the coupling elements carried by the latter.

Between the sides *a* and *a'* are fastened transverse frame members *r* and *r'*, carrying the draft sills *s* and *s'*. On the draft sills *s* and *s'* are mounted channel bars *t* and *t'* fastened to the end of sill *o* by a bent plate *u*. The opposite ends of the draft sills *s* and *s'* are connected to the end sill *o* by a bent plate *o*.

Between the channel bars *t* and *t'* is carried the upper coupling element *p*, and, at the opposite end, between the draft sills *s* and *s'* is carried the lower coupling element *p'*. Each of the coupling elements comprises guides *v* and *v'*, a detail of one of which is shown in Fig. 13. The guides for the lower coupling element *p'* are fastened to the inner sides of the draft sills *s* and *s'*, as shown in Fig. 9, and those for the upper coupling element *p* are fastened to the inner sides of the channel bars *t* and *t'*, as illustrated in Fig. 11.

In the guides *v* and *v'* are supported follower plates *w* and *w'*, on which are mounted the coupler yoke *z*, of the coupler bar *y*. In the coupler yoke *z* is contained a spring *z*. These parts are of the same construction at each end of the truck, and therefore

have been designated by the same reference letters.

Parts not described have no direct bearing on my invention, and may be of the usual, or any convenient construction. 70

I claim:

1. A logging truck, the combination of sides each consisting of a one piece metal flanged beam, journal boxes carried by the sides, the ends of the sides extending a substantial distance beyond said journal boxes, transverse end-sills secured to the flanges of the extensions of the sides, and coupling elements carried by said end-sills, the connection of the end-sills to the flanges of the opposing sides bracing said side extensions to resist bending due to blows delivered against them to thereby prevent the displacement of said end-sills and throwing out of alinement of the coupling elements. 85

2. In a logging truck, the combination of sides each consisting of a one piece metal flanged beam, said beam being recessed near both ends to receive pedestals, the ends of the sides extending a substantial distance 90 beyond said pedestal recesses, transverse end-sills secured upon the flanges of the similar end extensions of the respective sides and bracing said extensions with respect to each other, and coupling elements carried by the end-sills, the said end-sills preventing displacement of the extended ends of the sides under blows delivered against them to thus prevent the throwing out of alinement of the coupling members. 100

3. In a truck, in combination with side members having web portions provided with a rectangular recess at each end, pedestals seated and secured in said recesses, each of said pedestals consisting of a casting comprising horizontal and vertical flanges adapted to overlie the marginal web portions encompassing said recess, and transverse parallel inner vertical flanges spaced apart and projecting a substantial distance 110 beyond the side faces of the pedestals, thereby providing journal box bearings and having a domelike housing integral with the top portions of said transverse flanges for receiving the upper end of a spring. 115

4. In a truck, in combination with side members having web portions provided with a rectangular recess at each end, pedestals seated and secured in said recesses, each of said pedestals consisting of a casting comprising horizontal and vertical flanges adapted to overlie the marginal web portions encompassing said recess, and a companion flange spaced from, and parallel with the horizontal or top flange of the 125 pedestal, said top and companion flanges forming a groove in which to seat the web portions of the sides at said recesses.

5. In a truck, in combination with side members having web portions provided with 130

- a rectangular recess at each end, pedestals seated and secured in said recesses, each of said pedestals consisting of a casting comprising horizontal and vertical flanges adapted to overlie the marginal web portions encompassing said recess, and a companion flange spaced from, and parallel with the horizontal or top flange of the pedestal, said top and companion flanges forming a groove in which to seat the web portions of the sides at said recesses, and said pedestals comprising further transverse parallel inner vertical flanges spaced apart and projecting a substantial distance beyond the side faces of the pedestals, thereby providing journal box bearings, and having a dome like hous- ing integral with the top portions of said transverse flanges for receiving the upper end of a spring.
6. A pedestal consisting of a casting comprising lateral horizontally and vertically extending flange, a companion flange spaced from, and parallel with the horizontal flange, transverse parallel inner vertical flanges spaced apart and projecting a substantial distance beyond the face of the pedestal to provide a journal-box bearing, and a dome-like housing integral with the top portions of said transverse flanges for receiving the upper end of a spring. 20 25

ELBERT G. CHANDLER.
